His Attorney.

UNITED STATES PATENT OFFICE.

JOHN D. HILLIARD, OF SCHENECTADY, NEW YORK, ASSIGNOR TO GENERAL ELECTRIC COMPANY, A CORPORATION OF NEW YORK.

POWER SYSTEM.

Application filed September 18, 1923. Serial No. 663,510.

To all whom it may concern:

Be it known that I, JOHN D. HILLIARD, a citizen of the United States, residing at Schenectady, in the county of Schenectady, State of New York, have invented certain new and useful Improvements in Power Systems, of which the following is a specification.

My invention relates to electric power systems wherein line conductors are provided for transmitting current from one location to another, and has for its object the provision of means for protecting the line conductors of such systems against injury due to the accumulation of sleet upon them.

In the operation of transmission and distribution systems, line failures frequently occur due to overloading of the line conductors by sleet which produces excessive strain both on the lines themselves and the insulators by which they are supported.

In accordance with my invention, such failures are avoided by the use of a conductor having two conducting elements insulated from each other and normally connected in parallel but arranged to be disconnected at one end in response to the accumulation of sleet on an object in proximity to the line and to be automatically connected to a source of current for heating the loop thus formed. For this purpose use may be made of a cable with a conducting core insulated from the outer layers of wire by a layer of paper or the like impregnated by an insulating material, such as bitumen, which will not deteriorate when exposed to the weather, the entire cable being run through an impregnating bath to prevent the penetration of moisture between the strands if desired.

My invention will be better understood from the following description when considered in connection with the accompanying drawing and its scope will be pointed out by the appended claims.

Referring now to the drawing, Fig. 1 shows the application of my invention to a span or section of transmission line, Fig. 2 shows a detail of the apparatus illustrated by Fig. 1, and Fig. 3 shows a modified form of my invention.

Fig. 1 shows a transmission line 1 comprising conductors 2 and 3 insulated from each other throughout the span and permanently connected together at one end of the

span, as at the left hand end for example. Under normal conditions the conductors 2 and 3 are also connected to each other at the right hand end of the span by means of a switch blade 4 pivoted at the point 5 and arranged to be opened in response to the accumulation of sleet on a grid member 6 fixed to a lever 7 pivoted at the point 8 and mechanically connected to the blade 4 through a rod 9. At the opposite end of the lever 7 a counter weight 10 is provided for the purpose of maintaining the blade 4 in contact with the terminals 11 and 12. A current transformer 13 has its secondary winding 14 connected between the conductors 2 and 3 and its primary winding 15 connected between the conductor 3 and an adjacent span 16 of the transmission line. When the switch blade 4 is in closed position, current may be transmitted through the conductors 2 and 3 in parallel and the primary winding of the transformer 13 is short-circuited by the conductor 17. Upon movement of the switch blade 4 to its open position the conductor 2 is disconnected from the span 16 and the line current is carried by the conductor 3 connected in series with the primary winding 15 of the transformer 13, the secondary winding 14 of which is arranged to supply heating current to the circuit formed by conductors 2 and 3. The value of this heating current will of course depend on the value of the line current and the transformation ratio of the current transformer 13. The member 6, as indicated by Fig. 2, may consist of a frame 18 upon which is mounted a plurality of cross wires 19 for the purpose of facilitating the accumulation of sleet. While the member 6 is shown as horizontally arranged under normal conditions, it obviously may be made in the form of a sheet or slab and tilted for the purpose of preventing an accumulation of snow thereon.

Fig. 3 shows a modified form of the invention in which means are provided for melting an accumulation of snow or sleet off the grid member at the same time that heating current is caused to circulate through the conductors of the line. This modification comprises a lever 20 pivoted at the point 21 and having fixed to one of its ends an insulation member 22 around which are wound heating coils 23 connected

in parallel between one terminal of the primary winding 15 and a switch contact 24. The other end of the lever 20 is arranged to cooperate with a spring catch 25 mounted 5 on a base 26 upon which is also mounted a stop 27. The section 16 of the line is connected to the switch blade 20 through a conductor 28 and is mechanically supported by means of an insulator 29. Under normal 10 conditions the switch blade 20 is in the illustrated position and the secondary winding is short-circuited through contacts 30 and 31. An accumulation of snow or sleet on the grid member causes the blade 20 to 15 move downwardly out of engagement with contact members 30 and 31 and into engagement with contact 24 thereby connecting the primary winding 15 and the heating coils in series with the line. Melting of the sleet 20 or snow on the grid permits the switch blade 20 to automatically return to its normal position. The switch is thus repeatedly operated as often as necessary and is eventually left in its normal operating 25 position. It is evident that the heating of the main conductor should be greater than the heating of the resistance grid in order to insure that the main conductor is free from deposit before the switch returns to its normal 30 position.

While I have described the principle of my invention, together with the apparatus which I now consider to represent the best embodiment thereof. I desire to have it understood that the apparatus is only illustrative and that the invention can be carried out by other means.

What I claim as new and desire to secure by Letters Patent of the United States is,

40 1. An electric power system wherein conductors arranged to transmit current from one location to another are exposed to the weather, characterized by the fact that means responsive to an accumulation of sleet are 45 provided for causing said conductors to be heated whereby said conductors are protected from injury due to an accumulation of sleet upon them.

50 2. An electric power system comprising a conductor made of two conductive elements insulated from each other throughout their length and permanently connected together at one end, a switch for interconnecting said conductors at the other end, and means responsive to an accumulation of sleet for opening said switch.

55 3. An electric power system comprising a

conductor made of two conductive elements insulated from each other throughout their length, a transformer having its secondary windings connected between said elements, means for connecting said elements in parallel including a switch arranged to connect said elements together at one end and to short circuit the primary winding of said transformer, and means responsive to an accumulation of sleet for opening said switch to disconnect said elements from each other at one end and to connect the primary winding of said transformer in series with one of said elements.

4. The method of protecting a transmission line from injury due to an accumulation of sleet which comprises sending a heating current therethrough in response to the accumulation of sleet on an object located in proximity to said line.

5. A system of the class described comprising a conductor made of two conductive elements insulated from each other throughout their length, a current transformer having its secondary winding connected in series with said elements, means for connecting said elements in parallel including a switch arranged to interconnect said elements at a point near said transformer, and to short-circuit the primary winding of said transformer, and means responsive to an accumulation of sleet for opening said switch to disconnect said elements at the end adjacent the transformer and to connect said primary winding in series with one of said elements.

6. A system of the class described wherein conductors arranged to transmit current from one location to another are exposed to the weather, characterized by the fact that means responsive to an accumulation of sleet are provided for causing said conductors to be heated and by the further fact that said means are arranged to prevent an accumulation of snow upon itself.

7. A system of the class described comprising a conductor made of two conductive elements insulated from each other throughout their length and arranged to be connected in parallel, a switch for interconnecting said conductors at one end, and means responsive to an accumulation of sleet for opening said switch, said means comprising a conductor connected in series with said conductive elements when said switch is closed.

In witness whereof I hereunto set my hand this 17th day of September, 1923.

JOHN D. HILLIARD.
